ATTORNEY

UNITED STATES PATENT OFFICE.

HENRY P. GALE, OF ONEIDA, NEW YORK.

SHAFT-HANGER.

1,212,474.

Specification of Letters Patent. Patented Jan. 16, 1917.

Application filed June 2, 1916. Serial No. 101,247.

To all whom it may concern:

Be it known that I, HENRY P. GALE, a citizen of the United States, residing at Oneida, in the county of Oneida and State 5 of New York, have invented certain new and useful Improvements in Shaft-Hangers, of which the following is a specification.

This invention relates to shaft hangers and has for its object the provision of a 10 hanger in which adequate strength is combined with comparative simplicity of construction and consequent low cost of manufacture.

A further object of my invention is the 15 provision of a shaft hanger constructed largely of commercial metal shapes whereby the cost of manufacture is reduced to a minimum.

Further objects and advantages of my in- 20 vention will be apparent as it is better understood by reference to the following specification when read in connection with the accompanying drawing, illustrating the preferred embodiment thereof, in which—

25 Figure 1 is a side elevation of a hanger according to my invention; Fig. 2 is an edge view of the structure illustrated in Fig. 1; Fig. 3 is a horizontal section on the line 3—3 of Fig. 1; Fig. 4 is a horizontal section on the line 4—4 of Fig. 1, and Fig. 5 30 is an enlarged section on the line 5—5 of Fig. 1.

My improved shaft hanger comprises a head 5 of malleable cast iron or pressed 35 sheet steel constructed in the form of complementary sections 6, the sections 6 and 7 being secured together back to back by rivets or other suitable fastening means. The sections 7 are secured to the sections 6 by 40 bolts 8 having heads 9 disposed in suitable openings formed in the sections 6, nuts 10 engaging the bolts 8 to retain the parts in assembled relation.

Legs, each comprising a pair of com- 45 mercial angle bars 11 having their flanges tapered in opposite directions, as indicated in Figs. 1 and 2, are secured to the head 5 by disposing the abutting flanges of the angle bars between the complementary 50 members 6 of the head and inserting rivets or other suitable fastening means 12. A bar 13 is preferably secured to the abutting flanges of the legs to retain the legs in prop- 55 erly spaced relation.

Suitable feet 14 are constructed from com- 55 mercial angle bars, the bars being cut to the desired form, spread slightly to the desired angle and secured by rivets or other suitable fastening means 15 to the flanges of the legs. The feet 14 may be provided with slots 16 60 through which bolts may be inserted to secure the hanger in position.

From the foregoing it will be readily ap- 65 preciated that I have perfected a hanger of the utmost simplicity of construction, the parts being composed of commercial shapes which are readily obtainable in the market and easily cut to the desired form. The construction is such, furthermore, that a maximum of strength is combined with a mini- 70 mum of weight and these advantages in connection with the low cost of construction result in a hanger offering many advantages over devices of a similar character now known in the art.

75 It will be apparent that various changes may be made in the form, construction and arrangement of the parts without departing from the spirit and scope of the invention or sacrificing any of its material advantages, 80 the form hereinbefore described being merely a preferred embodiment thereof.

I claim:

1. In a shaft hanger the combination of 85 a head comprising integral complementary sections secured together back to back and forming the top and sides of said head and a bottom member secured to said sides, and legs consisting of angle bars secured together in complementary relation, the abutting flanges of said angle bars being secured 90 between the complementary sections of said head.

2. In a shaft hanger the combination of 95 a head comprising integral complementary sections secured together back to back and forming the top and sides of said head and a bottom member consisting of comple- 100 mentary sections secured together to said sides, legs consisting of angle bars secured together in complementary relation, the abutting flanges of said angle bars being secured between the complementary sections of said head, and feet consisting of angle bars secured to said legs.

3. In a shaft hanger, the combination of 105 a head consisting of integral complementary sections secured together back to back and

forming the top and sides of said head and a bottom member secured to said sides, legs consisting of angle bars secured together in complementary relation and having their flanges tapered in opposite directions, the abutting flanges of said angle bars being secured between the complementary sections

of said head, and feet consisting of angle bars secured to said legs.

HENRY P. GALE.
